UNITED STATES PATENT OFFICE

169,095

MUSIC BOX

John Petry, New York, N. Y., assignor to Raylite Electric Corp., Bronx, N. Y., a corporation of
New York

Application October 4, 1952, Serial No. 21,697

Term of patent 7 years

(Cl. D29—23)

To all whom it may concern:

Be it known that I, John Petry, a citizen of the United States and resident of New York, in the county of Queens, State of New York, have invented a new, original, and ornamental Design for a Music Box, of which the following is a specification, reference being had to the accompanying drawings forming a part thereof, and of which

Fig. 1 is a perspective view of a music box in open position, showing the ornamentation on the inside of one of the doors, both of which are identical.

Fig. 2 is a rear elevational view thereof.

Fig. 3 is a side elevational view of my music box shown in Fig. 1, the outside ornamentation of the open door being visible, both of which are identical.

I claim:

The ornamental design of a music box, as shown and described.

JOHN PETRY.
